UNITED STATES PATENT OFFICE.

CARL F. LUNDEBERG, OF HARTFORD, CONNECTICUT, ASSIGNOR TO UNDERWOOD TYPE-WRITER COMPANY, OF NEW YORK, N. Y., A CORPORATION OF NEW JERSEY,

TYPE-WRITING MACHINE.

1,113,227.

Specification of Letters Patent.

Patented Oct. 13, 1914.

Application filed December 2, 1909. Serial No. 530,904.

To all whom it may concern:

Be it known that I, CARL F. LUNDEBERG, a citizen of the United States, residing in Hartford, in the county of Hartford and 5 State of Connecticut, have invented certain new and useful Improvements in Type-Writing Machines, of which the following is a specification.

This invention relates to paper-feeding 10 and gaging devices for typewriting machines, and particularly those equipped for billing, in which it is desired to insert each bill or sheet in the machine a number of times, and also where it is desired to copy 15 the successive totals of many bills upon a single tally strip.

In order to keep a tally record upon one 20 piece of paper, of the individual items or of the totals of a number of bills, a tally strip or paper ribbon has been carried around the platen, means being provided to advance the tally strip each time the bill is line-spaced, when the amounts of the various items are 25 separately entered on the tally strip; or only between the entries of total amounts on the tally strip.

One feature of the invention is to improve 30 and simplify the tally strip feeding mechanism, and render it more reliable in operation, whereby the operator can control the winding or unwinding of the tally strip simultaneously with the forward or backward feed of the paper if desired, by rotating the platen forward or backward, to 35 make corrections or to enable the operator to line-space the paper and tally-strip by hand. The feeding mechanism is also made compact and simple, and easily and quickly operated. I may effect this by directly connecting the winding spool of the tally strip 40 mechanism and the platen by means of gears, so that rotation of the platen in one direction will wind the tally strip, and in the opposite direction will draw on the 45 wound up tally strip so as to unwind it, means being interposed between the platen and spool for enabling the rotation of the platen and spool independently.

Another feature of the invention is to improve 50 and simplify the tally strip mechanism whereby the paper rolls may be more easily placed and removed. I may effect this by mounting gudgeons in the opposite sides of the roll-supporting frame to enter

the opposite ends of the paper rolls, the gudgeons being retractable to permit the insertion and removal of the rolls. At least one of the gudgeons may be rotatable and has means for turning the roll.

Above the platen may be mounted a paper gaging device provided with gages for the leading and side edges of the paper, whereby when the usual pressure rolls are released or cast off, one or more sheets may be introduced around the platen and adjusted to the gages so that the first item and amount, and all succeeding items and amounts written thereon shall appear in alinement upon the written bill, even though the latter is withdrawn and inserted between the writing of each item.

Another feature of the invention is to improve, simplify and render more accurate the paper gaging mechanism, so that there may be no obstruction to the operator's view of the paper. This object may be obtained by providing a gage to overhang the tablet when the paper is to be alined, but normally lying behind the tablet where it is out of the way. The gage may be thrown into and out of effective position by the usual pressure roll release key.

A further object is to improve the paper gaging mechanism whereby the operator can easily obtain fine adjustments of the paper relative to the printing line, to print on the lines of ruled sheets, for instance. This advantage may be obtained by shiftably mounting the paper-arresting gage so that the adjustment of a lever will throw the gage away from or toward the printing line to vary the distance between the gage and printing line, as required, means being provided for detaining the gage in adjusted position. The gage is maintained parallel with the printing line at all times.

The paper gaging mechanism may be adjustable from end to end of the platen for sheets of different widths, a clip or locking device, including a pair of contractile jaws, being carried by the mechanism and biting upon a guide rod to releasably detain the mechanism in adjusted position against displacement in either direction. The jaws when squeezed together to release the rod, constitute a handle whereby to slide the paper-gaging mechanism along the platen.

By causing the right hand edges of the bills

2
to register with the right hand edge of the tally strip, through the paper-gaging mechanism, and by the insertion of a carbon paper between the bill and strip, the operator enters the amounts on the bills and tally sheets simultaneously. It is of great importance for the appearance of the bills and tally strip, and for the accuracy with which the amounts on the latter may be added at the end of a day to show the day's business, that the bills be successively registered with the tally strip by the paper gaging mechanism, so that the entries are printed directly beneath each other on the bills and tally strip. Other features and advantages will hereinafter appear.

In the accompanying drawings, Figure 1 is a perspective view of the platen and platen frame of an Underwood type of front strike writing machine, showing one embodiment of my invention applied thereto, parts being broken away to show the connection between the pressure roll release key, the paper-arresting gage, and the tally-strip feeding mechanism. Fig. 2 is an end view of the tally strip frame, the full lines showing it erected for use, the dotted lines indicating its folded position. Fig. 3 is a front view of the tally strip devices, parts being shown in section to illustrate the roll-supporting mechanism and the tally strip feeding mechanism. Fig. 4 is a detail perspective view of the tally strip feeding mechanism. Figs. 5 and 6 are detail views of the release key-actuated pawl for feeding the tally strip, when the pressure rolls are released, showing the pawl in and out of use, respectively. Fig. 7 is a detail perspective view of the clutch interposed between the platen and the winding spool, the parts being disassembled. Figs. 8 and 9 are detail cross sectional views taken at right angles to each other, of the clutch mechanism, showing the clutch in operative position. Figs. 10 and 11 are similar views of the clutch mechanism, showing the clutch in idle or released position. Fig. 12 is a detail rear perspective view of the paper-gaging mechanism, showing the paper-arresting gage in elevated position. Figs. 13 and 14 are detail edge views of the clip in effective position, and when released respectively. Fig. 15 is a detail end view of the paper-gaging mechanism, showing the paper-arresting gage elevated, as in Fig. 12. Fig. 16 is a detail rear view of the paper tablet and its gage, showing the lever connection between the two sections of the gage. Fig. 17 is a detail cross-sectional view, showing the paper-arresting gage rocked to its ineffective position. Fig. 18 is a detail rear view of the paper tablet and its gage, showing the link and lever connection between the gage sections whereby the gage is adjusted toward the printing line. Fig. 19 is a de-

tail cross-sectional view, similar to Fig. 15, but showing the spring between the gage and paper tablet. Figs. 20 and 21 are front and cross sectional views respectively, showing the spring clasp for maintaining the gage at different elevations. Fig. 22 is an end view, showing the connection between the key-actuated rock-shaft, the pressure rolls and the paper-arresting gage. Fig. 23 is a detail cross-sectional view showing the tally strip roll-holding gudgeons in retracted position, the roll being released.

A platen 1 is carried by an axle 2 journaled in a platen frame 3. The platen is line-spaced by a lever-driven slide 4 to which is pivoted a pawl 5, engaging a ratchet 6 on the axle 2.

The usual feed rolls 7, 8 engage the under surface of the platen 1, and are cast off from the platen by a release key 9 secured to a crank 10 journaled in the platen frame 3. A link 11 connects crank 10 with a crank 12 on a rock shaft 13 journaled beneath the platen and having flats 14 engaged by the ends of lever arms 15 supporting the pressure rolls 7, 8. To cast off the rolls, the release key 9 is depressed to rock the shaft 13, to bring the unreduced periphery thereof between the adjacent ends of the lever arms 15, thereby separating the latter against the tension of springs 16, as shown in Fig. 22.

The leading end of a tally strip 34 is inserted in a slit 39 (Fig. 3) in a winding spool 35 fixed upon shaft 21, having knobs 38.

A driving gear 40 on the platen axle meshes with an idle gear 41, which in turn meshes with a driving gear 42 on the winding shaft 21.

The operator can, by rotating the platen forward, turn the spool 35 to wind the strip as the work sheet is advanced, while the backward rotation of the platen will pull on and unwind the strip as the work sheet is fed backward.

To enable the rotation of the platen independently of the tally strip devices, and vice versa, the gear 42 is loose on winding shaft 21, and is secured to a clutch member 43. This loose clutch member has a flange or drum 43^a encircling a disk 44 fast on the winding shaft 21 and having a cut-away or cam portion 45 constituting with the flange 43^a, the walls of a raceway in which is located a ball or roll 46 of greater diameter than the throat of the raceway, and normally pressed between the converging surfaces by a spring 47. Rotation of the driver gear 42 and flange 43^a in only one direction viz., the direction of the arrow, Fig. 8, will cause the outer surface 43^a to roll the ball 46 farther up on the high point of the cam 45, thus closing the clutch to transmit the rotary motion of the platen to the winding shaft and spool. A reverse rotation of the driven gear 42 will roll the ball out of the

throat, and no motion will be imparted to the winding shaft.

To render the clutch inoperative, a disk 48 carries a bevel tooth or cam 49 to engage the roll or ball 46 on that side opposite the spring 47, and cam the ball outwardly, as shown in Fig. 10. A pin 50 engaging a hole 51 in the main clutch member 44 causes the disk to turn with the latter. The outer end 10 of the roll 46 may be beveled, as at 46^a, to facilitate the releasing action of the tooth 49.

The clutch is rendered inoperative by means of a shipper in the form of a cam shaft 52 adjacent the clutch release disk, 15 said cam shaft journaled in brackets 53, and rotated by a handle 54, and engaging disk 48 to move it against the tension of a returning spring 57. A cover 58 is placed between the clutch release and the open face 20 of the clutch. Upon giving the shaft 52 a quarter of a turn from the Fig. 3 position, the cylindrical periphery thereof locks the member 48 in position to hold the clutch ineffective, so the platen may be rotated independently of the tally strip mechanism.

I provide the crank 10 of the release key 9 with a link 9^a (Figs. 1, 4, 5 and 6) connecting it to an arm 60 loosely swinging on the winding shaft 21, said arm having a 30 spring-pressed pawl 61 releasably engaging a ratchet 62 fast on the winding shaft, whereby the shaft 21 is operable by the release key, independently of the clutch mechanism. At Fig. 6 the pawl 61 is shown as held 35 by its spring in a position of disuse, so that the key 9 can be operated without feeding the strip.

When the pawl 61 is in its operative position, it will be seen that every time the 40 pressure rolls 7 are cast off, the strip is advanced by said pawl 61. Thus if the strip is used for taking a carbon copy of matter written on sheets, the advance of the strip by pawl 61, each time the pressure rolls are 45 cast off to insert a new sheet, will cause the copy of one sheet on the strip to be separated from the copy of the next by a blank space.

The tally strip devices, including a roll-carrying frame 17, 20, are detachably mounted on the platen frame 3. The tally strip frame may be foldable to economize space when the machine is not in use, and comprises a base section 17 detachably secured by a catch 18 to a guide rod 19 extending between the ends of the platen frame; and a roll-carrying section 20 pivotally connected to the base. Winding shaft 21 may be journaled in the base section 17, 60 the roll carrying section 20 pivoted thereon to swing over and down upon the platen when the machine is not in use, as shown in dotted lines in Fig. 2. In erecting the roll-carrying section, the latter is swung upwardly and rearwardly until a stop 22 car-

ried thereby engages a shoulder 23 on the base section, the roll-carrying section being releasably held in erected position by a latch 24.

One or more tally strip rolls 25 are rotatably supported on the inner ends of gudgeons 26, 27, projecting into the space between the sides of the roll-carrying section 20 of the tally strip frame, and entering the hollow bores of the rolls. Preferably the gudgeons are mounted in and are retractable into hollow bearing boxes 28, 28^a on the sides of the frame, to release the rolls 25. The gudgeons are withdrawn by knobs 29.

For convenience in placing the roll or removing it, one of the gudgeons 26 is yieldingly detained out of use, by a spring-pressed detent 30 projecting into the box 28 to lie on one side or the other of a collar 31 on the gudgeon 26. At Fig. 3 said detent locks the gudgeon in working position.

The gudgeon 27 supporting the opposite end of the roll is pressed by a spring 33, and carries a disk 32, which presses the roll against the opposite side of the frame, producing a slight friction between the paper roll and the frame to prevent overthrow of the paper roll, or to prevent the strip from uncoiling from the roll faster than it is wound on the winding spool. The disk has spurs 37 taking into a core 36 upon which the tally strip is wound, so that rotation of the gudgeon by knobs 29 will turn the roll 25 to wind or unwind the strip.

The disk, spurs and inner end of the gudgeon, when withdrawn to release the roll, are accommodated in the enlarged inner end of the box 28^a, as shown in Fig. 23.

Tally strip mechanisms are usually employed when writing out bills or statements, so as to provide a check on the bills and afford a record of the day's business, the various amounts entered on the tally strip being added up at the end of the day. In order to facilitate such addition and moreover to properly align the bills or statements after insertion in the machine, paper gaging mechanism is employed in connection with the tally strip mechanism, such mechanism also permitting the right hand edges of the bill and of the tally strip to be registered so that the amounts may be entered on the bill and strip simultaneously and in vertical alignment. The paper-gaging mechanism also permits the alignment of the several items on the bill even though the latter is removed and reinserted after every item, as is often the case.

The release key is arranged to control a paper gage 63, associated with a paper-supporting tablet 64 carried by brackets 65 slidably mounted on the guide rod 19 to permit the tablet and gage to be shifted longitudinally of the platen, to accommodate sheets of different widths and to be moved over or

away from the tally strip to register the right hand edges of the bill and tally strip, if desired. The gage 63, by which the upper edge of the paper 85 is straightened while the pressure rolls 7, 8 are cast off, is normally in inaccessible or ineffective position beneath the tablet, but is shiftable into the path of the upper or leading edge of the paper, where it is accessible to permit the operator to adjust the leading edge of the paper, after which the gage is dropped back of the paper tablet, where it does not obstruct the paper, or the operator's view of the paper. The gage 63 is pivoted to the paper tablet at 66, and is pressed forward to overhang the outer sloping face of the tablet, by a spring 67. The gage rests against a stop 68 on the tablet. Upon depressing the release key 9, the rock shaft 13 is rotated to cast off the pressure rolls 7, 8, and also, to swing a crank 69 (Fig. 1) connected by a link 70 to an arm 71 on a rock shaft 72 journaled in the brackets 65, and having a finger 73 splined thereon.

The finger 73 lies adjacent an arm or plate 76 on the gage, and when the key 9 is depressed, the finger is rocked upward, as shown in Figs. 15 and 22, to permit the spring 67 to throw the gage 63 into operative position, simultaneously with the release of the pressure rolls, freeing the sheet 85 and allowing it to be adjusted against the gage 63. The cylindrical portions of shaft 13 mechanically hold the arms 15 apart against tension of springs 16, the key 9 is held depressed, and hence the gage is held in working position. The return of the key 9 rocks the finger 73 against the arm 76 to swing the gage 63 back of the tablet 64, as shown in Figs. 1 and 17. The finger 73 is connected to slide with the bracket 65 of the paper gaging mechanism on the shaft 72, to maintain an operative relation with the arm 76.

The gage is adjustable toward and from the printing line, so that a ruled line on the sheet can be brought to the printing line simultaneously with the engagement of the leading edge of the paper and the gage. The gage is made in sections, the lower one 63^a of which is pivotally secured to the tablet, at 66, the remaining section 63 being adjustably connected to the pivoted section, as by arms or levers 77, connected by a link 78 to rock in unison. By swinging the handle 79 on one of the levers, the gage section 63 is raised or lowered relatively to the tablet and the printing line, as shown in Figs. 12, 16 and 18, to effect fine variations and adjustments of the paper 85. The adjustable gage section is frictionally held at any point in its adjustment by a spring clasp 80 on the pivoted section 63^a, shown in Figs. 20 and 21, pressing against the gage section 63. The levers 77 serve as parallel arms to main-

tain the gage 63 parallel with the printing line throughout its range of adjustment.

The tablet carries a side gage 64^a by which the side edge of the paper 85 is alined, and the adjustment along the platen 70 of which the paper-gaging mechanism is capable, accommodates sheets of varying widths. To releasably lock the tablet and gage at any point in their adjustment along the platen, I provide the connecting bar 81 of the brackets 65 with a clip comprising a pair of jaws 82 having apertures 83 slightly larger in diameter than the diameter of the rod 19 which passes through the apertures, as shown in Fig. 15. The jaws tend to diverge or spread apart from each other and hence to bite or jam on the rod 19 and prevent endwise movement of the paper-gaging mechanism in either direction. To release the mechanism, the jaws are pinched or drawn together by the lips 84 carried by the jaws. The lips constitute a handle whereby the paper-gaging mechanism can be shifted endwise. When brought to the desired position, it is only necessary to release the lips, 90 whereupon the jaws 82 will spring apart and again grip the guide rod 19.

Variations may be resorted to within the scope of the invention, and portions of the improvements may be used without others, 95 as for instance the paper gaging device may be employed without the tally strip device.

Having thus described my invention, I claim:

1. In a typewriting machine, the combination with a platen, of a tally strip mechanism having a winding spool secured to a rotatable shaft, a shaft-operating mechanism including a train of gears extending from said platen, and a clutch interposed between the shaft-operating mechanism and the shaft, the clutch including an inner member fast on the shaft, an outer jaw driven from the shaft-operating mechanism and loose on the shaft, an element interposed between the fast and loose members for connecting and disconnecting them as the loose member is rotated in one direction or the other, and means for displacing the interposed element relative to the jaws to permit the independent rotation of the platen and winding spool in either direction.

2. In a typewriting machine, the combination with a tally strip mechanism having a winding spool secured to a rotatable shaft, 120 of a shaft-operating mechanism and a clutch interposed between the shaft-operating mechanism and the shaft, the clutch including an inner member fast on the shaft, an outer member driven from the shaft-operating 125 mechanism and loose on the shaft, an element interposed between the fast and loose members for connecting and disconnecting them as the loose member is rotated in one direction or the other, means for displacing the 130

interposed element relative to the jaws to permit the independent rotation of the shaft and platen, a shipper for shifting the clutch-engaging means, and a spring against whose tension the clutch-engaging means is shifted and held by the shipper when maintaining the jaws uncoupled, said shipper being mechanically held in working position.

3. In a typewriting machine, the combination with a platen and a tally strip mechanism having a winding spool secured to a rotatable shaft, of a train of gearing extending from the platen to the tally strip mechanism, and a clutch device interposed between the gearing and the spool to permit independent or synchronous rotation of the winding shaft and of the platen in one direction and independent rotation in the other direction.

4. In a typewriting machine, the combination with a platen frame, of a foldable tally strip frame including a base section releasably secured to the platen frame, a winding shaft rotatably journaled in the base section, a second section mounted to swing on the winding shaft, a winding spool on the shaft, means for mechanically turning the shaft, a paper spool journaled in the swinging section, and means for arresting the throw of the swinging section relative to the base section when erecting the frame.

5. In a typewriting machine, the combination with a platen, of a paper-supporting tablet, a sectional paper arresting gage pivotally mounted, yielding means tending to throw the gage into effective position relatively to the leading edge of the paper upon the tablet, and detaining means normally maintaining the gage in ineffective position relatively to the leading edge of the paper.

6. In a typewriting machine, the combination with a platen, pressure rolls therefor, tally strip devices, and a key for casting off and restoring the pressure rolls, and for feeding the tally strip, of a paper-supporting tablet, a pivotally mounted gage for alining the leading edge of the paper, a device to swing the gage into position and hold it there while the key is depressed.

7. In a typewriting machine, the combination with a platen, of a paper-supporting tablet on which the leading edge of the paper lies subsequent to its introduction into the machine, a spring-pressed shifting gage tending to overhang the tablet to arrest and enable the operator to straighten the leading edge of the sheet, an arm carried by the gage, and a device free from said arm when the gage is in effective position, but normally adapted to engage said arm to withdraw the gage.

8. In a typewriting machine, the combination with a platen, of a paper supporting tablet on which the leading end of the paper may lie subsequent to its introduction into

the machine, a spring-pressed shifting gage tending to overhang the tablet to arrest and to enable the operator to straighten the leading edge of the sheet, an arm on said gage, and a finger adapted to engage said arm to hold the gage normally in ineffective position, but adapted to be withdrawn to permit the spring to swing the gage to effective position.

9. In a typewriting machine, the combination with a platen, of a paper-supporting tablet adapted to be overlaid by the forward end of the sheet, a gage pivotally supported and spring pressed about its pivot to position to overhang the tablet or to rock behind the latter out of the way of the advancing sheet, said gage being adapted to be rocked to one or the other of its positions.

10. In a typewriting machine, the combination with a platen, of a pressure roll therefor, and releasing mechanism controlling the engagement of the rolls of the platen, said releasing mechanism including a key, of a paper supporting tablet above the platen, a shiftable gage overhanging the tablet to arrest the leading edge of the paper; and a mechanism operable by the key for throwing the gage to ineffective position behind the tablet position.

11. In a typewriting machine, the combination with a platen, of a paper-supporting tablet, a spring-actuated gage pivoted to the tablet and shiftable into and out of the path of the leading edge of the paper, a stop for arresting the gage, and mechanism for throwing the gage to ineffective position.

12. In a typewriting machine, the combination with a platen, of a paper-supporting tablet adjustable along the platen, a paper-arresting pivoted, spring-pressed gage shiftable relatively to the tablet, means whereby the gage may be shifted to effective or ineffective position, a rotatable shaft for actuating the shifting means, the latter slidably on the shaft and adapted to engage the gage shifting means in any position of tablet adjustment and means whereby the shaft may be rotated.

13. In a typewriting machine, the combination with a platen, pressure rolls therefor, and mechanism including a key for casting off and restoring the pressure rolls, of a paper-supporting tablet adjustable endwise of the platen, a paper-arresting gage shiftable relatively to the tablet, and gage-shifting mechanism between the pressure roll mechanism and the tablet, said gage-shifting mechanism including a rotatable shaft, a finger for controlling the position of the gage, the finger being splined on the shaft, and an arm on the gage engaged by the finger for effecting the shifting of the gage.

14. In a typewriting machine, the com-

- bination with a platen and its frame, of a paper adjusting tablet over the platen, a paper squaring gage carried by said tablet frame to effect fine adjustments of the paper relative to the printing line, and a spring adapted to press said gage into paper squaring position parallel with the printing line.
15. In a typewriting machine, the combination with a platen and its frame, of a paper adjusting tablet over the platen, a paper squaring gage carried by said tablet frame to effect fine adjustments of the paper relative to the printing line, a spring adapted to press said gage into paper squaring position parallel with the printing line, a guide rod, and a device for maintaining said platen in any position along said rod.
16. In a typewriting machine, the combination with a platen, and a paper supporting tablet, of a paper squaring gage shiftably mounted on said tablet to permit adjustment of the leading edge of a sheet of paper whereby the said sheet may be straightened, additional means whereby fine adjustments of the paper relative to the printing line may be effected, and means automatically holding said gage parallel with the printing line.
17. In a typewriting machine, the combination with a platen and a paper-supporting tablet, of a gage shiftable relatively to the tablet for permitting squaring of the leading edge of the paper, pivotally supported levers connected to the gage, and means for shifting the edge part of the gage relative to the tablet whereby fine adjustments of the paper relatively to the printing line may be effected.
18. In a typewriting machine, the combination with a platen and a paper-supporting tablet, of a gage shiftably connected with the tablet for permitting adjustment of the leading edge of the paper, pivotally-supported levers connected to the gage, a link connecting the levers, and a handle for swinging the levers to shift the effective edge part of the gage toward and from the printing line.
19. In a typewriting machine, the combination with a platen, feed rolls therefor, mechanism including a key for casting off and restoring the rolls, and a paper-supporting tablet, of a paper-adjusting gage shiftably mounted on the tablet, pivotally supported levers connected to the gage, mechanism operated by the key to permit the gage to move to working position, or to withdraw the gage to permit advance of the paper, and separate mechanism for shifting the gage relatively to the tablet whereby fine adjustments of the gage relatively to the printing line may be effected.
20. In a typewriting machine, the combination with a platen and a paper-supporting tablet, of a paper-adjusting gage mount- ed on the tablet, pivotally supported levers connected to the gage, and means to insure a parallel motion of the gage toward and from one edge of the tablet.
21. In a typewriting machine, the combination with a platen and a paper-supporting tablet, of a paper-adjusting gage shiftably pivoted on the tablet and having one edge adjustable to have a parallel motion toward and from one edge of the tablet and levers for effecting said adjustment.
22. In a typewriting machine, the combination with a platen, a paper gaging mechanism, comprising a frame carrying a tablet having a gage at one end for the side edge of the paper, and a guide rod relative to which the frame is slidable, of a pair of spring-actuated jaws on the frame, having apertures through which the rod passes, the jaws being yieldingly retained in divergent position to bite upon the rod and prevent displacement of the tablet in either direction.
23. In a typewriting machine, the combination with a platen and platen frame having a guide rod, a paper gaging mechanism adjustable on the rod and having a side edge gage, of a clip carried by the paper-gaging mechanism for maintaining the mechanism in adjusted position, comprising a plurality of divergent spring-actuated jaws biting upon the rod to prevent displacement of the mechanism in either direction, and means for releasing the jaws constituting a handle for sliding the mechanism along the rod.
24. In a typewriting machine, the combination with a platen and platen frame, the latter having a guide rod between its ends, and a paper gaging mechanism including a side gage for the side edge of the paper, adjustable along the rod, of a clip carried by the paper gaging mechanism to maintain it in adjusted position, comprising a plurality of jaws having apertures through which the rod passes, the jaws normally inclined relatively to each other to bite upon the rod, and lips carried by the jaws by which they may be drawn together to release the rod when adjusting the paper gaging mechanism, the lips forming a handle by which to adjust the paper-gaging mechanism on the rod.
25. In a visible typewriting machine, the combination with a platen, of a paper-gaging mechanism located above the platen and including a paper-supporting tablet onto which the leading edge of the paper is fed, a shiftable gage to which the leading edge of the paper may be adjusted, and a gage engaging device normally in engagement with said gage, but movable out of engagement therewith when the gage is in effective position, for holding said gage normally out of effective position may be shifted to a position behind the paper, as it is advanced.

over the paper tablet, to avoid obstructing the operator's view of the paper.

26. In a typewriting machine, the combination with a platen, pressure rolls therefor, and tally strip devices, of a paper-supporting tablet, a sectionally adjustable spring-pressed gage to which the leading edge of a sheet may be adjusted, and a single key for effecting the casting off and restoration 10 of the rolls relatively to the platen, the feeding of the tally strip and for swinging the gage behind the tablet out of the path of the leading edge of the sheet, the gage being spring-pressed into operative position.

27. In a typewriting machine, the combination with a strip roll holder and a platen about which said strip passes, of a pressure roll coöperating with said platen, a tablet on which a sheet may lie, a gage for the sheet 20 on the tablet normally behind the tablet, pivotally supported levers connected to the gage, and means for moving said pressure roll to and from said platen, and means connected to said moving means arranged to 25 move said gage from and permit it to be moved into position to aline the sheet.

28. In a typewriting machine, the combination with a strip roll holder and a platen about which a strip passes from said holder, 30 of a pressure roll coöperating with said platen, a strip reel, driving means for said strip reel, a tablet on which a sheet may lie, a gage for the sheet lying behind said tablet when said pressure roll is against the 35 platen, and means for causing said strip reel to wind and for enabling said gage to move to operative position when said pressure roll is released from said platen and means whereby the pressure roll may be released 40 from the platen upon the insertion of paper into the machine.

29. In a typewriting machine, the combination with a strip roll holder and a platen about which said strip passes, of a pressure 45 roll coöperating with said platen, a key for casting off said pressure roll, a strip reel, disengageable connecting means between said strip reel and the platen, and a drive for said strip reel for advancing it when said 50 key is operated to cast off said pressure roll.

30. In a typewriting machine, the combination with a strip roll holder and a platen about which said strip passes, of a pressure roll coöperating with said platen, a key for 55 casting off said pressure roll, a strip reel, a driving gear connection between said strip reel and the platen, comprising a clutch which releases when said reel is advanced independently of the platen, and means for

winding said strip operated by said key for 60 casting off said pressure roll.

31. In a typewriter, the combination with a platen and a feed roll, of a key for casting off said feed roll, a tablet on which paper may be lined up for the platen, a gage for 65 said paper constantly spring-pressed into operative position, means holding said gage in ineffective position when said roll contacts with the platen, and a connection from said key for releasing said holding means 70 when the rolls are released from the platen.

32. In a typewriter, the combination with a platen and a feed roll, of a key for casting off said feed roll, a tablet on which paper may be lined up for the platen, a gage for 75 said paper constantly spring-pressed into operative position, said gage having an adjustable edge, means for holding said edge at each end, a single arm for adjusting both ends at once, means holding said gage in 80 ineffective position when said roll moves into contact with the platen, and a connection from said key for releasing said holding means when the rolls are released from the platen.

33. In a typewriter, the combination with a platen and a feed roll, of a key for casting off said feed roll, a tablet on which paper may be lined up for the platen, a gage having an edge that is adjustable, for said 90 paper means for adjusting both ends of said edge at once, and means for moving said gage into position as said roll is moved from the platen, and moving said gage to ineffective 95 position when said roll moves into contact with the platen.

34. In a typewriting machine the combination with a platen, of a tablet above the platen and a paper gage provided with an adjustable edge part pivotally mounted on 100 the platen, and parallel arms on said edge part which are mounted in adjustable parallelism with the main part of the gage.

35. The combination of a removable platen, a feed roll therefor, a key to release said 105 feed roll, a tally strip winding mechanism operable simultaneously with the feed roll release, means whereby the tally strip winding mechanism may be released to run idle, and means connecting the tally strip winding mechanism with the platen to pull the tally strip backward when the platen is turned backward.
